(57) **CLAIM**

The ornamental design for a latch as shown and described.

DESCRIPTION

This application is related to U.S. patent application Ser. No. 29/925,937, filed Jan. 26, 2024, entitled Cooler, the entire disclosure of which is hereby incorporated herein by reference.

This application is also related to U.S. patent application Ser. No. 29/925,940, filed Jan. 26, 2024, entitled Handle, the entire disclosure of which is hereby incorporated herein by reference.

FIG. 1 is a front perspective view of a latch showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a view of the latch in an environment of use;

FIG. 9 is an enlarged view of portion 9 in FIG. 8.

FIG. 10 is an exploded view of FIG. 9; and,

FIG. 11 is a view similar to FIG. 9 but in an alternative configuration.

The portion of the latch shown in broken lines in FIGS. 1-3, 6, and 8-10, which portion forms a recess, illustrates an unclaimed portion of the latch and forms no part of the claimed design.

The other broken lines in FIGS. 8-10, and the additional broken lines in FIG. 11, illustrate unclaimed environmental structure that also forms no part of the claimed design, which unclaimed environmental structure includes a cooler.
